DIESEL ENGINE

Francis H. Stroud, Seattle, Wash., assignor to
 Johnson Manufacturing Co., Seattle, Wash., a
 corporation of Washington

Application June 13, 1932, Serial No. 616,764

7 Claims. (Cl. 123—59)

My invention relates to internal combustion engines of the Diesel type.

One of the principal objects of my invention is to devise an engine of this type which shall be extremely simple and compact, and which in particular shall achieve these objects by elimination of valve gear or moving parts especially intended for the control of the air.

10 A further object is the provision of a rigid and practical construction, whereby weaving and vibration of the engine at all speeds shall be practically eliminated.

15 It is a further object to provide an engine of this type which, by reason of its simplicity, compactness and the elimination of various working parts, shall be light in weight per unit of power.

20 With these and like objects in view, my invention comprises the novel parts, and the novel combination and arrangement thereof, as shown in the accompanying drawings, described in the specification, and as will be more particularly defined by the claims which terminate the same.

25 In the accompanying drawings I have shown my invention embodied in a form which at present is preferred by me.

Figure 1 is a side elevation, with parts broken away and shown in section, illustrating such an engine.

30 Figure 2 is a vertical axial section through one of a pair of cylinders in such an engine.

35 Figure 3 is an elevation of the block wherein are formed the compression chambers, substantially on the line 3—3 of Figure 2, and Figure 4 is a transverse horizontal section substantially on the line 4—4 of Figure 2.

40 Figure 5 is a fragmentary vertical axial section through the second cylinder of a pair, the first of which is illustrated in Figure 2, but showing parts advanced by a quarter of the whole cycle.

45 The major engine parts, as herein shown, comprise a composite cylinder including the working section 1, the cylinder head 10 secured thereon, the block 2 whereon the working section rests, and which in turn rests upon the bed plate 3 to form the crankcase. The working piston 11 is reciprocable in the bore 12 of the cylinder 1 to open the air inlet port 13 and the exhaust port 14 at the bottom of the piston's stroke.

50 Secured to the bottom of the skirt of the working piston 1 is a compression piston 4 reciprocable within the compression section of the composite cylinder defined by the bore 20 of the block 2. The connecting rods 30 connect the stepped pistons with the crank shaft 31.

I prefer that the crank shaft be balanced, as indicated by the balancing members 32.

The block 2 is divided horizontally by a partition 21, thus defining an upper chamber 22 and a lower chamber 23. Valves 5 and 50, which 60 may be alike and which may constitute simple check valves, control inlet of air into the respective chambers 22 and 23. Preferably the air is screened coming through the aperture at 51. The block 2 may also be partitioned, as 65 indicated at 24 (see Figure 4), vertically from top to bottom, to separate those chambers 22 and 23 which pertain to each pair of cylinders, and thus each pair of cylinders cooperates and may be designated No. 1 and No. 2 cylinders, or, 70 for convenience, cylinders A and B (see Figures 3 and 4).

Cylinder A, the No. 1 cylinder, has a port 25 at its upper end which communicates directly with the upper chamber 22. Cylinder B, or No. 75 2 cylinder of the pair, has a port 26 which discharges through a downwardly extending passage 26' into the lower chamber 23. From the upper chamber 22 a port 27 affords communication with a passage 17 in the cylinder 1, the 80 purpose of which will appear hereafter, but which, it may be stated, leads eventually to discharge within the cylinder 1, that working section which pertains to the cylinder B. From the lower chamber 23 a passage 28' leads to a port 28 85 corresponding to the port 27 and communicating with the port 17 of the working section which corresponds to the cylinder A, or No. 1 cylinder.

As is explained in my copending application Serial No. 616,765, filed June 13, 1932, the working piston 11 has a chamber 15 formed therein immediately beneath its working head, this chamber affording a through passage between the passages 17, which are in effect the sources of air under pressure for the individual cylinders, at one side of the cylinder 1, and a port 16 which, being in communication with the port 13, effects a by-pass of the gas when the piston is at the bottom of its stroke, so that at this time, and only at this time, air under pressure in the passage 17 is admitted through the chamber 15, the ports 16 and 13, into the bore 12, forcing out the spent gases through the now uncovered exhaust port 14.

The paired pistons of No. 1 and No. 2 cylinders, or those designated A and B, are arranged to operate in alternate manner. One is at the top of its stroke when the other is at the bottom, and vice versa. Considering the No. 1 or A piston to be at the bottom of its stroke, as seen 110

in Figures 1, 2 and 4, air which was previously compressed in the lower chamber 23 is permitted to pass into the bore 12 to scavenge it, as previously explained. The piston, upon rising, 5 covers the ports 13 and 14, traps the air therein, and further compresses it. At the same time the annular compression piston 4, rising in its bore 20, compresses air which is in this bore by virtue of the free communication between this 10 bore and the upper chamber 22 through the port 25. This air, of course, has been drawn in past the check valve 5, but upon the commencement of the compression stroke of this particular piston 4 the valve 5 closes and the compression 15 proceeds, in this bore and also in the communicating chamber 22.

This upper chamber 22, it will be remembered, was in free communication with the passage 17 for cylinder B through the port 27. However, 20 the working piston in this cylinder B has started downward on the power stroke, but has not yet uncovered its ports 13 and 14, nor have the ports of its through passage 15 come into communication with the respective ports 16 and 17. 25 In consequence, there is no escape of pressure from the upper chamber 22. When the piston B does reach the bottom of its stroke, the gas compressed in the upper chamber 22 is now released through the piston B and into the cylinder 30 B, and as this piston now starts upward, its piston 4 commences to compress the air which is in its bore by virtue of the free communication through the passage 26' and port 26 communicating with the lower chamber 23. This air 35 had been drawn in past the check valve 50, but as compression commences, the valve 50 closes, and as in the previous instance, the compression cannot escape through the open port 27 for the reason that the piston in cylinder A has 40 started downward on its power stroke, but has not brought its ports into communication with those in its own cylinder.

From this it can be seen that simple check 45 valves 5 and 50, and the arrangement of ports 5 in the block 2, in the cylinder 1 and in the piston 11, very simply control the compression and admission of air, and of course, the discharge of the spent gases.

Because of the passages 26' and 28' extending 50 through the upper chamber 22, it is best to dispose the horizontal partition 21 somewhat more than half way down from the top of the block 2. Thus the volumes of the two chambers 22 and 23 may be equalized to the end that the compression 55 in each of them for a given piston displacement is the same.

The block 2 is well braced by the partitions and passages which have been described, and by the several bores 20 extending therethrough. No 60 special pipe fittings or connections are required; machine work is reduced to a minimum. The working sections 1 are readily supported upon this block, and the block in turn is readily and directly connected to the bed plate 3. All may 65 be locked together by the long bolts 6. This forms a simple and rigid construction which practically eliminates weaving, and because the crank shaft is balanced, and there is no valve gear rotating at high speed, offset from the general 70 vertical plane of the engine, vibration is cut down to the minimum, and for all practical purposes is eliminated. This is a factor of large importance, adapting the engine for use upon vessels, upon steam shovels, logging equipment, 75 and the like, where vibration is destructive to

equipment and harmful to the operator or to those on board a vessel.

What I claim as my invention is:

1. An engine having its cylinders arranged in pairs, each cylinder of a given pair including a working and a compression section, and said engine including a hollow block having an upper compression chamber freely communicating with the compression section of one cylinder of a given pair and adapted to communicate with the working section of the other cylinder of such pair; and said block having also a lower compression chamber freely communicating with the compression section of such other cylinder of the pair and adapted to communicate with the working section of the first cylinder, and working and compression pistons reciprocable within the respective cylinders. 80

2. An engine having composite cylinders arranged in pairs, each of said composite cylinders comprising a working section and a compression section in coaxial arrangement, stepped working and compression pistons reciprocating in the respective cylinders, said engine including a hollow block partitioned to define lower and upper compression chambers having check-valve-controlled inlets, the working section of one composite cylinder of a given pair being in free communication with the lower compression chamber at such time as the working piston of such cylinder is at the bottom of its stroke, and the upper end of the compression section thereof being in free communication at all times with the upper compression chamber; and the working section of the other composite cylinder of such given pair being in free communication with the upper compression chamber at such time as the working piston of such cylinder is at the bottom of its stroke, and the upper end of the compression section thereof being in free communication at all times with the lower compression chamber; and means to effect reciprocation of said pistons in alternate manner, thereby to compress air in each compression section and associated chamber for timed discharge into the paired working cylinder. 90

3. In an engine, a hollow block partitioned to define an upper and a lower chamber having outlet ports, and said block also having cylinders arranged in pairs, each cylinder including a compression section formed in said hollow block and extending through said chambers and a working section above and coaxial with the compression section, the upper end of the compression section of one composite cylinder of each pair communicating with the upper chamber, and the working section communicating with the outlet port of the lower chamber; and the upper end of the compression section of the other composite cylinder of each pair communicating with the lower chamber, and the working section communicating with the outlet port of the upper chamber; check-valve-controlled inlets to the respective chambers, and stepped working and compression pistons reciprocable in alternate manner in the paired cylinders, to close the outlet from each chamber upon the compression stroke of the piston in the compression chamber discharging thereinto, until the end of the power stroke of the piston in the paired chamber receiving therefrom. 100

4. An engine comprising a hollow block and having paired cylinders, each cylinder including a compression section and a working section above and coaxial with the compression 105

section, said hollow block being partitioned to define upper and lower compression chambers, the working section of one cylinder of a pair being adapted to communicate with the lower compression chamber and the compression section of such cylinder always freely communicating with the upper compression chamber; and the working section of the other cylinder of such pair being adapted to communicate with the upper compression chamber and the compression section of such other cylinder always freely communicating with the lower compression chamber; and working and compression pistons reciprocable within the respective paired cylinders to control compression and discharge of air within the chambers.

5. An engine of the type described comprising a hollow block and having two or more composite cylinders disposed in pairs, each cylinder 10 including a compression section defined by boring said hollow block and a working section adapted to be supported on said block coaxially with the compression section, the block being 15 interiorly partitioned to define upper and lower compression chambers, the compression sections

having open discharge ports, that of one composite cylinder of a given pair communicating directly with the upper chamber, and a passage extending from the compression section port of the other composite cylinder of such given pair 20 through the upper chamber and the partition to afford free communication with the lower chamber, the block being ported to afford communication of the working section of such other composite cylinder directly with the upper chamber, and the block having a passage extending through the partition and the upper chamber to afford free communication from the lower chamber to a port in the block for the working section of the first composite cylinder 25 of such given pair.

6. The combination of claim 5, and the block having check-valve-controlled inlet ports for each chamber.

7. The combination of claim 5, the partition 30 being disposed nearer the bottom of the block to compensate in volume for the volume of the passages through the upper chamber.
